UNITED STATES PATENT OFFICE.

MARC RESEK, OF CLEVELAND HEIGHTS, OHIO, ASSIGNOR TO THE CLEVELAND METAL PRODUCTS COMPANY, OF CLEVELAND, OHIO, A CORPORATION OF OHIO.

WICK CLEANER.

Application filed May 11, 1922. Serial No. 559,987.

To all whom it may concern:

Be it known that I, MARC RESEK, a citizen of the United States, residing at Cleveland Heights, in the county of Cuyahoga and State of Ohio, have invented a certain new and useful Improvement in Wick Cleaners, of which the following is a full, clear, and exact description, reference being had to the accompanying drawings.

10 My invention relates to means for cleaning wicks of oil burners. This act when properly done involves removing the char, smoothing down the end of the wick and shaping it to a well defined and even edge 15 so that it will produce a perfect flame.

The primary object of the invention is to provide a device which may be readily used by persons, however inexperienced they may be, for cleaning wicks of oil burners 20 and which by reason of its character insures a proper performance of the acts above enumerated.

Other objects of the invention are to provide a device of the aforesaid character 25 which, when rotated in one direction, will clean and shape the wick and, when rotated in the reverse direction, will smooth or iron out the wick; to provide a wick cleaner or trimmer having a cutting edge that is inclined to the direction of its travel so that it will produce a shaving action on the wick and shear the wick in a lateral direction rather than in a direction parallel with the direction of travel, as in a radial direction 30 rather than a circumferential direction when used in conjunction with tubular wicks; to provide a wick cleaner or trimmer of the aforesaid character wherein the cutting parts do not contact with the metal parts 35 of the burner to the end that said burner parts will not be scratched or worn away by the use of the cleaner; to provide a device of the foregoing character which in its cleaning operation picks up and retains 40 the char that is removed from the wick and prevents its falling into the burner or from lodging upon parts of the burner which support elements that are required to bear an accurate relation to the wick; to provide a 45 device of the aforesaid character which is designed for use with a burner involving a wick stop and which is so related to the stop that only a limited amount can be removed 50

from the burned portion of the wick, thereby insuring a definite relation between the wick 55 stop and said portion; and to provide an implement of the aforesaid character which is designed especially for use with burners involving air distributing members or flame spreaders and which in the performance of 60 its work maintains a uniform space between the burned portion of the wick and the adjacent air directing portion of the distributing member or flame spreader.

Further objects will become apparent as 65 this description proceeds, among which are the provision of a comparatively simple and inexpensive device, preferably constructed entirely of sheet metal stampings, and through which the objects already enumerated 70 are effectually attained.

Several embodiments of the invention are illustrated in the drawings accompanying and forming a part hereof and wherein Fig. 1 shows a burner in sectional side elevation 75 with the present preferred form of my wick cleaner in operative position; Fig. 1^a is an enlargement of a part of Fig. 1; Fig. 2 is a top plan view of the device; Fig. 2^a is a sectional detail on the line 2^a—2^a of the preceding view; Fig. 3 a bottom plan view of the device; Fig. 4 is a sectional view through the burner, at right angles to Fig. 1, showing an air distributing member or flame spreader applied to it; Fig. 5 is a fragmentary sectional side elevation of a burner having associated with it another form of my invention; Fig. 6 is a bottom plan view of the cleaner shown in Fig. 5; Fig. 7 is a view, similar to Fig. 5, illustrating a further 80 modification of the invention; Fig. 8 is a plan view of what is shown in Fig. 7, the burner parts being indicated in dot-and-dash lines; Figs. 9 and 10 are sectional side elevations of the upper portion of a burner 85 showing associated therewith a form of my invention which interlocks with the wick stop mechanism, the former view illustrating the parts as they are when the wick is down and the cleaner is resting on the wick tubes, and the latter view showing the parts with the wick at the limit of its upward movement and the cleaner supported by a part of the structure in a given relation to the wick; Fig. 11 is a plan view of the form 90 of the invention illustrated in Figs. 9 and 105

10; Fig. 12 is a fragmentary section through what is known as a "giant" burner which is sometimes incorporated in stoves employing also the smaller burners shown in the 5 preceding views, and the form of the invention illustrated in connection with this larger burner involves two cleaners of sizes corresponding to the two sizes of burners so that it may be used with both; and Fig. 10 13 is a top plan view of the cleaner illustrated in Fig. 12.

Reference may be had to the application of Lee S. Chadwick, Serial No. 528,813, filed January 12, 1922, and entitled Automatic wick stops, for a full and complete disclosure of the type of burner in connection with which I have herein illustrated my present invention; and an application filed by said Lee S. Chadwick and myself 20 on the same date, and bearing Serial No. 528,833, contains a full and complete disclosure of the air controlling member or flame spreader, with the latch mechanism for locking it to the wick stop mechanism, 25 shown in Fig. 4 of the present case.

With particular reference to Figs. 1 and 4, the burner comprises, generally, inner and outer wick tubes 1 and 2, respectively, which are joined together at their lower ends by an 30 annular wall 3, thereby to enclose a wick space 4 that contains a tubular wick 5, supported by a wick carrier 6 having a member 7 applied to its lower end. The member 7 has a radial arm 8 extending inwardly 35 into an offset 9 of the inner wick tube. A rod 10 has its lower end secured to the arm 8 and its upper end extended through a sleeve 11 that rises from the top wall 12 of the offset 9. The upper end of the rod 10 40 is connected to a rack member 13 which extends downwardly and with a toothed portion 14 whereof a pinion 15 meshes. The pinion is secured to a wick raising spindle 16 journaled in opposed parts of a bracket 45 17 that is applied to and depends from the offset portion 9 of the inner wick tube, said bracket having an opening through which the rack member 13 reciprocates. A hand wheel 20 is applied to the forward end of 50 the spindle 16, and a ratchet wheel 21 is secured to the rear end thereof. Supported for vertical movement within the upper end of the inner wick tube is an annulus 25 that has secured to it a frame 26, the lower end 55 of which is held slidably engaged with the lower portion of the bracket 17 by overturned portions 27 and 28 of said bracket. The portion 28 is offset from the body portion of the bracket 17 enough to receive between it and said body portion the lower end 60 of the frame 26 and a pawl carrying member 30 that is pivoted at 31 to said frame. The member 30 carries a resilient pawl 32, the nose 33 whereof is adapted to engage the 65 teeth of the ratchet wheel 21, and it is limit-

ed in its movement by a stop 34 which consists of a plate that is attached to the member 30 and which has a notch that embraces the pawl, all of which is fully disclosed in the above mentioned application of Lee S. 70 Chadwick.

Pivoted supported, through pins 40, from the upper end of the frame 26 are latching elements or tumblers 41 that are limited in their pivotal movement and maintained in proper relation to the frame by hooks 42 that are engaged through openings 43 in the tumblers.

An air controlling member or flame spreader 45 is adapted to be inserted within 80 the upper end of the burner and to rest upon the annulus 25. Said member or flame spreader has an annular shoulder 46 over and into engagement with which the keeper portions 47 of the tumblers 41 are adapted 85 to be moved by a pin 48 when its tapered lower end is inserted between the tumblers. The pin 48 is guided within a hole in the top wall of the spreader and through a member 49 depending from said wall, its 90 upward movement with respect to the spreader being limited by the engagement of a shoulder 50 on the pin with the member 49. The pin is equipped with a head 51 by means of which it may be grasped when 95 lifting the spreader, the pin serving as a manual lifter for the spreader as well as an automatic actuator for the latching means. The weight of the pin causing it to descend and spread the tumblers and engage them 100 with the shoulder 46 as above described. The air distributing member or spreader 45 incorporates a flange 55 disposed above the wick.

By reference especially to the above mentioned Chadwick application, it will be seen that when the wick is turned down, the flange 55 descends into the wick space a material distance below the upper ends of the wick tubes. To raise the wick, the spindle 16 is rotated, by means of the hand wheel 20, to the right as the parts are herein illustrated, the driving connections between the spindle and wick being effected through the pinion 15, rack member 13, rod 10 and member 7. As the wick rises it engages the flange 55 of the flame spreader and lifts the flame spreader. By reason of the connection of the flame spreader with the frame 26, through the latch mechanism above described, the frame is lifted and with it the pawl carrying member 30. It may be explained that when the parts are in normal condition with the wick down, the nose of the pawl 32 is below the reach of the teeth of the ratchet wheel 21, and that the pawl carrying member is restricted to a substantially vertical course during its initial movement by the overturned portion 28 of the bracket 17. During the incipient upward 115 120 125 130 movement of the pawl 32, the nose of the pawl 32 passes over the teeth of the ratchet wheel 21, and the pawl carrying member 30 is lifted by the pawl 32, the pawl 32 being resilient and being urged 135 upward by the weight of the flame spreader 45.

movement of the frame 26, the pawl carrying member is lifted to present the nose of the pawl 32 to the teeth of the ratchet wheel 21 so that said ratchet wheel picks up the pawl and, through said pawl, the member 30, and frame 26, lifts the annulus 25 and consequently the flame spreader which rests thereon, removing the flange of the flame spreader from the wick. This movement continues until the rotation of the pawl carrying member 30 is arrested by the engagement of its stop 56 with the edge of the frame 26, in which position the parts are shown in Fig. 4. Since the pinion 15 and the ratchet wheel 21 are secured to the spindle 16, the spindle is restrained against further rotation and the wick against further upward movement. Consequently, a fixed relation is established between the upper end of the wick and the adjacent edge of the flange 55. It is understood, of course, that the wick may be adjusted between its "high" position and its lowest burning position, which latter position is in the vicinity of the upper ends of the wick tubes, but the wick must never approach the flange more closely than in the relation established as aforesaid. In view of this I have taken the "high" position of the wick as the most favorable condition under which to clean it by means of my improved device. Therefore, I have shown the wick in "high" position in Fig. 1 as being acted upon by the cleaner.

In its present preferred form, my improved cleaner comprises a body portion 60 which may be formed of sheet metal with a cylindrical lower portion 61 and a correspondingly shaped upper portion 62 of a lesser diameter and which is joined to the portion 61 by an inclined wall 63. A sleeve 64 surrounds the portion 61 and is substantially co-extensive therewith. At its lower end the sleeve is flanged inwardly, as at 65, and at its upper end is flared outwardly to provide a wick engaging flange 66 which, with the inclined wall 63 of the body 60, forms a trough. The wick engaging flange 66 has a taper corresponding to that of the upper end of the wick, and preferably equally spaced about the flange 66 are tangential slots 67. Adjacent the corresponding edges of the several slots the material of the flange is curled upwardly, as indicated at 68, while the edges opposite the portions 68 are made sufficiently sharp to constitute cutting blades 69. In actual practice, I employ a comparatively thin metal and swage the edge portion sufficiently to remove any burr which may be produced from the stamping operation, and in case heavier metal is employed, the edge may be swaged, chamfered or otherwise treated to make it sharp enough to serve the intended purpose. A wick sizer 70, in the present instance in the form of an annular channel member that is substantially U-shaped in cross section, is applied to the underside of the wick engaging flange adjacent its periphery, the edge of the inner flange of said member abutting the under surface of the wick engaging flange inwardly of the outer ends of the slots 67, while the edge portion of the outer flange of said member is curled about the edge of the flange 66, as shown at 71, thereby to secure the wick sizer in place. The sleeve 64, of which the wick engaging flange 66 is a part, may be secured to the portion 61 of the body 60 by indentations, spot welding, soldering, or other suitable means.

In using this form of my invention, the wick is turned to "high" position in the manner previously described and necessarily while the flame spreader 45 occupies its position in the burner. The flame spreader is then lifted from the burner by grasping it by the knob 51 of the pin 48, the initial upward movement of the pin releasing the locking elements or tumblers 41 so that they are at liberty to swing inwardly away from the shoulder 46 of the flame spreader and allow the flame spreader to be bodily lifted from the burner through the instrumentality of the pin 48. The user then grasps the cleaner by the reduced upper end of the body 60 and lowers it into the top of the burner until the bottom flange 65 bears upon the annulus 25, the proportions being such that when the bottom flange bears upon the annulus, the wick engaging flange 66 bears with a proper degree of pressure upon the charred top of the wick. While the wick sizer 70 extends below the upper end of the outer wick tube and is intended to cooperate therewith for the purpose of centralizing the cleaner within the burner, it is enough larger in diameter than said tube to be spaced therefrom very slightly during the cleaning operation so as not to scratch or wear the end of the wick tube. The relations are best illustrated in the enlarged detail of Fig. 1^a.

With the cleaner in place, the user rotates it alternately in opposite directions a distance at least somewhat greater than the distance between the slots 67. As the device is herein illustrated, when it is turned to the right, the blades 69 shear the char from the wick, and, when rotated in the opposite direction, the edge portions 68 smooth or iron out the surface of the wick. By reason of the inclination of the slots, a desirable shaving action is produced in a direction tending to flare the wick outwardly at its upper end. The wick is restrained from undue flaring, however, by the sizer 70, the edge of the wick being confined within the angle between the sizer and the wick engaging flange and having thus imparted to it a smooth and even edge which insures a perfect flame.

The char which is removed from the wick falls into and is retained by the trough formed by the flange 66 and the wall 63 and is thus prevented from falling upon the 5 annulus 25 or other parts of the burner.

It will be seen from the foregoing description that by the use of the cleaner a definite distance is established between the annulus 5 and the upper end of the wick. Therefore, when the cleaner is removed and the flame spreader is returned to its position within the burner, a proper spacing between the upper end of the wick and the flange 55 of the spreader is assured.

15 In the form of the invention illustrated in Figs. 5 and 6, the body 75 of the cleaner has its lower end flanged at 76, and its other end equipped with a knob 77 by means of which the device may be turned. As in the former 20 instance, the body portion 75 is made up of cylindrical portions of different diameters with a shoulder 78 between them, and to this shoulder is secured the wick engaging flange 79 which is provided with slots 80, 25 corresponding to and being of the same nature as the slots 67 of the former embodiment. In this modification the sizing of the wick is accomplished by elements 81 which are formed of strap metal, terminating in lugs 82 at their ends by means of which they are secured to the flange and having depending loops adjacent their ends which extend through slots 83 in the flange and a central upwardly extending loop 84. The sizing 30 elements are shown as of like number with the slots 80 and as spaced midway between them. Obviously there may be any desired number of either the slots or sizers. The 35 operation of this form of the invention is practically identical with that of the form 40 above described.

In Figs. 7 and 8 I have shown a cleaner comprising a body 85, having a crank 88 applied to its upper end by means of which 45 the cleaner may be turned when resting with its lower end upon the annulus 25. Studs 90 extend outwardly and upwardly from the peripheral portion of the body 85 and carry tapered rollers 91 which engage 50 the upper end of the wick, the axes of the rollers preferably radiating from the center of divergence of the upper end of the wick. Blades 92 are journaled upon the 55 studs 90 between the rollers and the adjacent part of the body 85 and their cutting edges are arranged to bear upon the top of the wick. In this form of the invention the blades shear off the carbon with an angle cut, as in the previous instances, and 60 the rollers 91 serve to smooth the wick.

With the forms of the invention above 65 described, I depend upon the air distributing member or flame spreader for throwing into operation the wick stop mechanism which determines the "high" or trimming

position of the wick. In the modification illustrated in Figs. 9, 10 and 11, and which I shall next describe, the cleaner itself incorporates means for throwing the wick stop mechanism into operation, obviating the use 70 of the air distributing member or flame spreader for this purpose.

This form of the invention comprises, generally, two relatively movable units. The first, which I shall designate A, comprises a body 95 which corresponds in shape with the body of the flame spreader and which incorporates a shoulder 46^a into engagement with which the keeper portions 47 of the locking elements or tumblers 41 are 75 adapted to be engaged when said elements or tumblers are spread apart by the pin 48^a, the unit A being properly positioned in the burner by the engagement of its base flange 96 with the annulus 25. Attached to the body 80 95 for rotation with respect thereto is a member 97 having a series of peripheral depending prongs 98 which align with and are adapted to extend through slots in the wick engaging flange 100, which is a part of the second unit designated B. The flange 100 is carried by a sleeve 101 which loosely surrounds the lower portion of the unit A and has applied to its underneath side a wick 85 sizer 102. Opposed to the depending flange 95 of the wick sizer is a flange 103 of an annular member that occupies the lower portion 100 of the wick engaging flange and which is adapted to centralize the device within the burner by cooperation with the upper end of the inner wick tube. The sleeve 101 and member 97 are held against relative turning 105 by a finger 105 that rises from one side of the sleeve 101 and extends through a slot 106 in the member 97.

With the wick down, as shown in Fig. 9, the cleaner is inserted into the upper end of the burner and its base flange 96 comes to rest upon the annulus 25 thus positioning the shoulder 46^a in locking relation to the elements 41 so that when the pin 48^a is released and allowed to descend, its tapered lower end spreads the elements 41 so that their keepers 47 engage said shoulder to lock the unit A to the frame 26 precisely as a flame spreader is locked to said frame. The wick engaging flange 100 rests upon the upper ends of the wick tubes, and the prongs 98 of the member 97 extend through the slots in the wick engaging flange and into the wick 110 space of the burner. When the wick is raised, it engages the prongs 98 and, through them and the member 97, lifts the unit A and with it the frame 26 to throw the wick stop mechanism into operation, exactly as hereinbefore described. Immediately the frame 26 is elevated at a considerably higher rate of speed than that at 115 which the wick is traveling which causes the body 95 to be lifted to the position shown 120 125 130

in Fig. 10. At a given point in its upward travel, the base flange 96 of unit A picks up the sleeve 101 of unit B and lifts the wick engaging flange 100 to what corresponds with the "high" position of the wick, the wick following until its upper end is engaged with said flange. With the parts in this condition, the operator may rotate unit B, the device functioning in its cleaning operation like the forms already described. The slots of the wick engaging flange 100 are designated 107.

In certain types of oil stoves there are burners of different sizes. In Fig. 12 I have indicated a larger burner, known as a "giant" burner, which is used in stoves also employing the smaller burners illustrated in the preceding views; and I have shown associated with the "giant" burner a form of my invention incorporating cleaners for the wicks of both "giant" and smaller burners. The body 110 of the composite cleaner terminates at its lower end in an enlarged cylindrical portion 111 that is surrounded by a sleeve 112, flanged inwardly at 113 below the corresponding end of the portion 111, and which flares outwardly at its upper end to provide a wick engaging flange 114 to the edge portion of which is applied the wick sizer 115. The flange 114 is provided with slots 116 for trimming and smoothing the wick. Set within the smaller end of the body 110 is an element 120 constituting the cleaner for the wicks of smaller burners. The element has, at one end, a base flange 121 and, at its opposite end, an enlargement 122 which fits within the body 110. Between the enlargement 122 and the smaller end there is an inclined wick engaging flange 123 which is provided with slots 124 for trimming and smoothing the wick. The smaller end of the body portion 110 is curled over and inwardly against the wick engaging flange 123 to provide a wick sizer 125. The manner of using this form of the invention is obvious from the explanation given hereinbefore in connection with the other forms.

Having thus described my invention, what I claim is:

1. A device for cleaning circular wicks, said device being adapted to be inserted within the upper end of the wick and having an annular flange engaging the top of the wick, said flange being provided with a series of slots extending across the wick, the edge portions adjacent the corresponding sides of the various slots serving as cutting edges for removing char from the wick, while the opposite edge portions are formed to smooth the wick, the edge portions acting to perform their respective functions when the device is rotated alternately in opposite directions.
2. A cleaner for cylindrical wicks of tubular burners that is adapted to be inserted within the upper end of the burner and positioned thereby, said cleaner having an outwardly extending flange adapted to engage the top of the wick, said flange having slots extending diagonally across the top of the wick, the edge portions adjacent corresponding sides of the various slots constituting cutting blades for removing char from the wick when the cleaner is rotated in one direction, the edge portions adjacent the opposite sides of the slots being formed to smooth the wick when the cleaner is rotated in the opposite direction, and a wick sizer depending from the peripheral portion of the flange and arranged to be engaged by the edge portion of the wick.
3. A cleaner for cylindrical wicks of tubular burners wherein the top surface of the wick diverges upwardly, the cleaner comprising a body adapted to be inserted within the upper end of the burner, and an inverted frusto conical flange extending outwardly from the body portion for engagement with the top surface of the wick, said flange having slots that extend diagonally across the wick, the edge portions adjacent the corresponding sides of the several slots constituting cutting blades for removing char from the wick when the cleaner is rotated in one direction, while the edge portions adjacent the opposite sides of the slots are turned upwardly so as to smooth the wick when the cleaner is rotated in a reverse direction, the inclination of the cutting edges being such as will cause the upper end of the wick to be flared outwardly, and a wick sizer depending from the peripheral portion of the flange and wherewith the edge portion of the wick engages.
4. A wick cleaner of the character set forth comprising a cylindrical body portion, a sleeved member applied to the lower end of said body portion and having an outwardly flared upper end constituting a wick engaging flange, a series of slots in said flange, the edge portions adjacent the corresponding sides of the several slots constituting cutting blades for shearing char from the wick when the cleaner is rotated in one direction, the edge portions adjacent the opposite sides of the slots being formed to smooth the wick when the cleaner is rotated in the reverse direction, and a wick sizer applied to and depending from the peripheral portion of the wick engaging flange and wherewith the edge portion of the wick engages.
5. In combination with a burner incorporating stop means for positioning the burned end of the wick at a definite elevation, a device including a wick cleaning element, said device cooperating with the burner in such manner as to locate the cleaning element in a position to remove a

limited amount of material from the wick when the wick is at the aforesaid definite elevation.

6. In combination with a burner incorporating a supporting part and wick stop mechanism for positioning the burned end of the wick in a given position with respect to said supporting part, a cleaner including a cleaning element that is presented in operative relation to the burned end of the wick when another part of the cleaner is engaged with the supporting part of the burner and the burned end of the wick is in the aforesaid given position.

15 7. In combination with a burner incorporating a supporting part and wick stop mechanism for positioning the burned end of the wick in a given position with respect to said supporting part, a wick cleaner including a cleaning element that is engaged with the burned end of the wick when the same is in the aforesaid given position and a part of the cleaner is brought to rest upon the aforesaid supporting part of the burner, 20 the cleaning element serving to remove the char from the wick when the cleaner is moved with respect to the burner on said supporting part.

8. In combination with a burner incorporating a wick, an air distributing member, and means establishing a definite relation between the wick and said member thereby to properly position the wick for cleaning, and further means adapted to be maintained 30 at a given elevation by cooperation with the burner for cleaning the wick when it occupies the aforesaid position.

9. In combination with a burner incorporating wick raising means, wick stop mechanism, and an air distributing member, the air distributing member having a part arranged to be engaged by the wick and through which the member is elevated when the wick is raised, operative connections 40 through which movement of the air distributing member couples the wick stop mechanism with the wick raising means thereby to stop the wick at a given elevation, and a wick cleaner adapted to assume 45 the position of the air distributing member 50 in the burner and including a cleaning element that is presented in operative relation to the burned end of the wick when the cleaner is in such position.

55 10. In combination with a burner incorporating wick raising means, wick stop mechanism that is movable into operative connection with the wick raising means, said mechanism involving a supporting 60 member, an air distributor adapted to rest upon the supporting member and have interlocking engagement with the wick stop mechanism so as to move therewith, the air distributor having a part disposed within 65 the path of the wick so that when the wick

is elevated it will engage said part and lift the distributor, the movement of said distributor being transmitted to the wick stop mechanism so that said mechanism is coupled with the wick raising means, the stop 70 mechanism arresting movement of the wick raising means when the burned end of the wick has attained a given elevation, and a wick cleaner adapted to assume the position of the air distributor upon the aforesaid 75 supporting member, the cleaner including cleaning means presented in operative relation to the burned end of the wick when the cleaner rests upon said member.

11. In combination with a burner incorporating wick raising means, wick stop mechanism movable into operative connection with the wick raising means, a member movable with the wick stop mechanism, and a device adapted to rest upon said member 80 and have locking engagement therewith so as to be movable with the member, the device having a part disposed in the path of the wick so as to be engaged and moved by the wick when the wick is raised thereby to 85 couple the wick stop mechanism with the wick raising means and arrest movement of the wick raising means when the burned end of the wick has attained a given elevation, the device including a wick cleaning element 90 that is disposed in operative relation to the burned end of the wick when said end of the wick occupies the aforesaid elevated position.

12. In combination with a burner incorporating wick raising means and wick stop mechanism arranged to be coupled with said means, a cleaner adapted to have operative connection with the wick stop mechanism and including a part disposed in the path of the wick so that when the wick is elevated it will engage said part and move 100 said cleaner to couple the wick stop mechanism with the wick raising means, the stop mechanism serving to arrest movement of the wick raising means when the burned end of the wick has attained a given elevation, the cleaner including a wick cleaning element 105 that is positioned in operative relation to the burned end of the wick when said end has attained the aforesaid elevation.

13. In combination with a burner incorporating wick raising means and wick stop mechanism arranged to be coupled with said means, a cleaner including two relatively 110 movable units, the first of said units being adapted to have locking engagement with the wick stop mechanism and having a part disposed in the path of the wick so that when the wick is elevated it will engage said part and lift said unit to effect a coupling 115 of the wick stop mechanism with the wick raising means, the wick raising means being capable of a limited movement after the wick stop mechanism is coupled there- 120 125 130

with, said means acting to lift the first unit with its aforesaid part beyond the reach of the wick and to raise the wick with its burned end at a given elevation, the second 5 unit of the cleaner including wick cleaning means that is supported by the first unit in substantially the plane of the burned end of the wick.

14. In combination with a burner incorporating wick raising means, wick stop mechanism movable into and out of driving connection with the wick raising means, a cleaner incorporating two units that are relatively movable in a vertical direction, 15 the first unit being arranged to have interlocking engagement with the wick stop mechanism so as to be movable therewith and having elements extending over and arranged to depend into the wick space of the 20 burner, the second unit including a wick engaging flange having openings wherewith said elements register, the wick when elevated serving to lift the first unit through its engagement with the aforesaid elements 25 thereby to move the wick stop mechanism and couple it with the wick raising means, the wick raising means having a limited movement after the wick stop mechanism has been coupled with it and serving during such limited movement to lift the first 30 unit and elevate the aforesaid elements beyond the "high" position of the wick, a part of the first unit engaging a part of the second unit to lift the latter so that its wick 35 engaging flange is disposed in operative relation to the wick, said flange having wick cleaning parts which remove the char from the wick when the cleaner is rotated with respect thereto.

40 15. A wick cleaner comprising a body, a

flange extending therefrom for engagement with the burned end of the wick, a plurality of slots in said flange, the edge portions whereof serve as cutting elements for removing char from the wick, and a plurality 45 of wick sizers supported in spaced relation to each other by said flange, each sizer comprising a strap having depending loops that straddle the wick and one of which is adapted to be engaged by the edge 50 of the wick.

16. A composite wick cleaner of the character set forth comprising a circular body, a wick engaging flange surrounding and exterior of one end of the body, a wick sizer 55 applied to the peripheral portion of said wick engaging flange, and a flange surrounding the interior of the opposite end of said body, the adjacent end of the body being extended beyond the last mentioned flange to 60 constitute a wick sizer, said flanges having slots the edge portions whereof constitute wick cleaning blades.

17. In combination with a burner incorporating a wick, a device including a cutting part for removing material from the burned end of the wick, and means for supporting the device in operative relation to the burner with its cutting part spaced from any metallic parts of the burner. 65

18. A wick cleaner for tubular wicks comprising an inverted frusto-conical member having a part for removing char from the wick and which is adapted to be applied to the top of the wick and rotated with respect 75 thereto whereby said part will form on the wick an upwardly diverging top surface.

In testimony whereof, I hereunto affix my signature.

MARC RESEK.
